UNITED STATES PATENT OFFICE

2,124,067

NEEDLE BAR ASSEMBLY FOR KNITTING MACHINES AND PROCESS OF KNITTING THEREON

Kenneth Howie, Norristown, Pa., assignor to Wildman Mfg. Co., Norristown, Pa., a corporation of Pennsylvania

Application December 14, 1935, Serial No. 54,470
Renewed January 5, 1938

9 Claims. (Cl. 66—82)

The invention relates to full fashioned knitting machines of the Cotton type.

The invention includes a needle bar made of sections i. e. a middle section and a section at each end of the middle section, said end sections being adjustable endwise away from the middle section to leave enlarged spaces in the needle row between the adjacent ends of the sections so that a wale of enlarged sinker loops will be knit in each heel tab substantially at or adjacent the inner selvage thereof.

In transferring the leg blank to a machine for knitting the foot portion onto the leg portion, the wale of open stitches can be used for impaling the heel tabs onto the transfer bar, and thence to the needles of the footer machine. Or the fabric, having the wale of enlarged loops, can be impaled on the needles of the same machine on which they were formed, for continuing the knitting to form the foot, or the tabs with the wales of enlarged loops can be used in a process involving the attachment of said tabs to the foot portion of the stocking by a looping action performed by the operator.

The invention also includes besides the apparatus, the process of knitting, and the fabric.

In the accompanying drawings

Fig. 1 is a front view of the needle bar adjusted to its closed position, and showing part of the means for operating the bar.

Figs. 1a and 1b are details.

Fig. 2 is a front view of the needle bar adjusted to its open position.

Fig. 3 is a detail plan view of parts of adjacent sections of the needle bar and part of the means for adjusting the sections of the bar to open or closed position. This view shows the sections in their separated relation, the bar therefor being referred to as in its open condition.

Fig. 4 is a detail plan view of the sectional clamping member of the needle bar.

Fig. 5 is a detail plan view of the main part of the sectional needle bar.

Fig. 6 is a plan view of the supporting rail of the sectional needle bar.

Fig. 6a is an end view of Fig. 6.

Fig. 6b is a view of an end plate for the rail of Fig. 6.

Fig. 7 and Fig. 7a are end views of the main part, and the clamping part, respectively, of the needle bar.

Figs. 8 and 9 are views of a bar forming part of the means for adjusting the sections of the needle bar.

Figs. 10 and 11 are views of an eccentric form-

ing another part of the means for adjusting the needle bar sections.

Fig. 12 is a diagram of the fabric produced with the aid of the sectional needle bar.

The sectional needle bar can be used in an ordinary Cotton frame for making full fashioned hosiery, or in the machine shown in the United States patent of Howie and Krieble, December 4, 1934, No. 1,982,991.

The needle bar of the present invention in which the row of spring beard needles *d* are mounted is shown generally at *1*, *1a*, carried by brackets *2*, mounted on bearings *4* and operated by mechanism substantially as in ordinary practice, upwardly and downwardly and also forwardly and backwardly in performing the knitting operations.

This needle bar according to the present improvement is formed in sections, i. e., a middle section *1* and end sections *1a*, for a purpose hereinafter described.

The sections of the bar are each provided with a dovetail base *1x* corresponding to the recess in the carrier rail. At the ends of the carrier rail *11* are cross plates *11b* secured by screws *12*. The center section of the needle bar is fixed to the carrier rail by screws *13*. The end sections are adapted to have movement lengthwise along the carrier rail to and from the center section, the outward movement being limited by the adjustable stop screws *11c*. The needles are clamped between the main sections of the needle bar and the complementary clamping sections *1c* which are secured to the main section by the bolts *1d*. Each main section of the needle bar may have one of the clamping members associated therewith, so that each end section with its clamp can be manipulated independently.

The movable end sections *1a* of the needle bar are pressed normally endwise against the ends of the fixed middle section *1* of the bar by springs *14* which are seated in sockets *14a* of the cross plates *11b* and sockets *15* in the end sections.

The closed position of the needle bar, i. e. with the end sections against the middle, is shown in Fig. 1, so that the needles adjacent the joint between the sections are spaced apart a distance equal to the spacing of the needles throughout the sections. This condition is for knitting courses with the spacing of stitches uniform throughout, as for instance, in the welt, leg and foot portions of the stocking.

For separating the end sections from the ends of the fixed middle section, as shown in Fig. 2,

55

- various means may be provided. The one shown as an example consists of an eccentric 76, Figs. 1, 2, 10 and 11 pivoted on a screw 77 mounted in the right hand end section of the needle bar. 5
 5 This eccentric bears on the end of a rod 78 slidably mounted on the needle bar by screws 79 passing through elongated openings 80 in the rod into the end sections of the needle bar. An adjustment for this connection consists of a screw 82
 10 passing through the lug 83 and bearing on one of the screw studs 79, a lock nut being provided at 84.

The eccentric may be variously operated automatically or manually. As an example, a manually operated means has been chosen for this 15 particular disclosure of the invention consisting of a handle 84 attached to the eccentric. By turning this handle from the position shown in Fig. 1 to that shown in Fig. 2, the rod 78 is pushed by the eccentric leftward, and this movement is communicated to the lefthand section of the needle bar. The right hand section 1a of the needle bar is also free to move and because the eccentric is mounted directly thereon the result will be that both end sections are moved 20 endwise from the middle section until stopped by the screws 77c. The needles will now be related as shown in Fig. 2 with the needles at the adjacent ends of the sections of the bar spaced apart as shown at y a distance greater than the 25 ordinary spaces between the needles.

With the needle bar sections adjusted as just described, a line of sinker wale stitches will be formed longer at the gaps, or wider spaces y between the sections of the needle row, so that 30 the heel tabs will have a line of enlarged spaces, or openings, in those wales of the heel tabs which are at or adjacent the inner selvage edges of said tabs, as shown at y^2 Fig. 12, which selvage edges are knit on, say, the end pairs of needles of the 35 middle section of the needle bar, one pair at each end of said middle section.

The clamping screws 1d for the center section of the needle bar, as well as the clamping screw for the right hand section, which screws draw the 40 clamping plate 1c into place to clamp the needles to the bar, have their heads exposed through openings 78a in the rod 78, which openings are larger in diameter than the bolt heads, so that the rod is free to be adjusted despite that the said heads lie 45 in part in said openings.

With the invention applied to a stocking knitting machine, it is possible to provide in the heel tabs of the stocking blank during the knitting thereof a line of enlarged openings in a wale of 50 each heel tab, said wale preferably being spaced apart from the selvage edge of the heel tab with two ordinary standing wales intervening. These 55 large openings are due to the spaced apart relation of the needles at the points y where the adjacent ends of the sections lie spaced apart.

The sectional needle bar above described may be used in carrying out various processes of knitting. For instance, when it is desired to provide in the knitting operation a wale of open work in 60 each tab to facilitate impaling the leg blank onto a transfer bar for transferring to a machine for interknitting the foot portion of the stocking with the leg portion, the knitting of the leg would be carried on with the needle bar in closed condition 65 to provide a row of needles equally spaced throughout. This knitting would be continued to a point where the knitting of the heel tabs is about to begin, whereupon the needle bar is adjusted to its open position of Fig. 2 presenting 70 the extra wide spaces at y between certain of the

needles which are to form the heel tabs. The knitting is continued, during which the instep fabric is cast off after the required ravel courses are knit thereon, and finally the heel tabs with their ravel courses are cast off and the fabric 5 is then ready to be placed on the points of a transfer bar and thereafter upon the needles of the footer machine by the use of said transfer bar.

Other processes can be carried out involving the use of what, conveniently, may be termed an 10 instep transfer bar, by which the instep loops are taken off from the instep needles, and held while the heel tabs are completed and thereafter, by means of said instep transfer bar, replaced upon 15 said instep needles for knitting the foot portion of the fabric on the same machine, only the one machine being necessary to do the whole work.

This instep transfer bar forms part of the subject matter of another application for patent filed of even date herewith, as does also its combination 20 with this needle bar.

In one process, involving the use of said instep transfer bar, the heel tabs having the wale of open work stitches may be spread outward or laterally and their enlarged sinker wale stitches 25 impaled upon the needles of the same machine which has formed the leg portion and then the knitting of the foot is proceeded with on the same machine, it being understood that the instep transfer bar which took the instep loops off 30 from the instep needles and held them, has now restored said loops to the instep needles, this having taken place before the knitting of the foot has been started.

It will be noted that the row of needles for 35 forming the instep fabric extends from and including the needle $d1$ to and including the needle $d2$, on the middle section of the needle bar. At the ends of this row of instep needles there are other needles on the middle section, and two of these are shown as an example at each end of the middle section. These needles, while mounted on the middle section, belong to those needles which knit the heel tabs. By this relation of the needles the sectional bar enables the extra wide spaces y^2 45 to be provided in the heel tab fabric at or adjacent the inner selvage edges thereof.

The full complement of needles is always maintained in alignment with the needle row, the extra wide spaces between certain of the needles being obtained by a relative adjustment endwise 50 between the sections. Because none of the needles are moved to a position out of alignment with the other needles of the row, the use of operating connections individual to certain of the 55 needles is avoided, which operating connections would have to be multiplied according to the number of needles which are to be operated to and from a position of alignment with the other needles of the row.

The sectional bar may be used in carrying out other processes of knitting a single unit full fashioned stocking on one machine, and therefore it will be understood that the invention involving the sectional needle bar is not limited 65 to any one use thereof.

By this invention the needles are maintained in their aligned condition irrespective of whether or not the extra wide spacing at y exists in the needle row.

No individual needle is dropped out nor deflected from its prescribed position. No special means are provided for holding the needles in alignment with each other. All sections being mounted in the rail having the dovetail channel 75

will be maintained in accurate alignment under all circumstances. The dovetail channel in the supporting rail may be lined with any suitable wear piece.

5 It will be seen that the rail 71 which serves as carrier for the sections 1, 1a holding the needles is integral from end to end. Its middle portion i. e. that portion which corresponds in length to the middle section 1 of the needle bed has said 10 middle section rigidly attached thereto against any relative movement between said middle section and the rail. The portions of the rail lying at either end of the rail may be termed the end portions of said rail. They form integral extensions of the rail's middle portion and they serve 15 as guides as well as supports for the end sections 1a of the needle bed.

I claim:

1. A needle bar for full fashioned knitting machines comprising a carrier rail made up of a 20 middle portion and end portions integrally connected with the middle portion and in lengthwise alignment therewith, a section rigidly secured to the rail's middle portion against movement relative thereto, a section mounted on each of the 25 integrally connected end portions of the rail and slidably only endwise for adjustment to and from the middle section while in constant alignment therewith, needles carried by the sections and 30 means for operating the end sections for adjusting them.

2. A needle bar according to claim 1 in which the operating means for the end sections comprises a bar and an initial operating element for 35 said bar mounted on one of the sections, and a connection operated by said element, which by one action moves both of the end sections away from the middle section.

3. A needle bar according to claim 1 in which 40 spring means holds the needle bar sections closed against each other, and initial operating means mounted on one of the sections, with a connection operated thereby for separating the sections against the pressure of the spring means.

45 4. A needle bar for flat full fashioned knitting machines having a middle section and a section

at each end of the middle section movable to and from the middle section, each section having its complement of needles to make up the needle row, and means for moving the end sections endwise relative to the middle section, said means comprising an initial operating element for manual manipulation mounted on one of the end sections, a connection from said element to the other end section, and stops for limiting the outward movement of the end sections, substantially 10 as described.

5. A needle bar according to claim 4 in which the operating means consists of an eccentric mounted on one end section, and a connection operated by and extending from the eccentric to 15 the other section, substantially as described.

6. The herein-described process of knitting with a sectional needle bar consisting in knitting the leg portion of the stocking with the sections closed, that is, with the end sections closed 20 against the middle section to provide equal spacing between the needles throughout the needle row, then separating the sections so that the spaces between the needles at the adjacent ends of the sections will be enlarged for making a 25 wale of enlarged sinker loops adjacent the inner selvage edges of the heel tabs, substantially as described.

7. A process according to claim 6 in which the inner selvage portions of the heel tabs are formed 30 by needles at the ends of the middle section of the needle bar.

8. The herein-described process of knitting with a sectional needle bar, consisting in knitting a portion of the fabric with the sections closed, to 35 provide equal spacing between the needles throughout the needle row, then separating the sections so that the spaces between the needles at the adjacent ends of the sections will be enlarged, and then knitting to thereby make wales of enlarged sinker loops, substantially as described. 40

9. A method according to claim 8 in which all sections of the needle bar are held in lengthwise alignment under all conditions, substantially as described.

KENNETH HOWIE.
